US00D987547S

(12) **United States Design Patent** (10) Patent No.: **US D987,547 S**
(45) Date of Patent: **** May 30, 2023**

(54) **ROOF FOR VEHICLE**

(71) Applicant: **Polaris Industries Inc.**, Medina, MN (US)

(72) Inventors: **Scott T. Mazour**, Detroit Lakes, MN (US); **James A J Holroyd**, Stillwater, MN (US); **Carl D. Christensen**, North Branch, MN (US); **Brian T. Utter**, Greenbush, MN (US); **Ian M. Dunn**, Chanhassen, MN (US)

(73) Assignee: **Polaris Industries Inc.**, Medina, MN (US)

(**) Term: **15 Years**

(21) Appl. No.: **35/002,190**

(22) Filed: **Dec. 6, 2021**

(80) **Hague Agreement Data**

Int. Filing Date: **Dec. 6, 2021**

Int. Reg. No.: **DM/219708**

Int. Reg. Date: **Dec. 6, 2021**

Int. Reg. Pub. Date: **Apr. 1, 2022**

(51) **LOC (14) Cl. 12-16**

(52) **U.S. Cl.**

USPC **D12/404**

(58) **Field of Classification Search**
